UNITED STATES PATENT OFFICE.

ROBERT M. CLARK, OF NEWTON, MASSACHUSETTS, AND JOHN G. BENNETT,
OF PITTSBURG, PENNSYLVANIA.

PROTECTOR FOR IGNITING MATERIAL IN SIGNAL-TORCHES.

No. 836,563.

Specification of Letters Patent.

Patented Nov. 20, 1906.

Application filed August 13, 1902. Serial No. 119,556.

To all whom it may concern.

Be it known that we, ROBERT M. CLARK, residing at Newton, in the county of Middlesex and State of Massachusetts, and JOHN G. BENNETT, residing at Pittsburg, in the county of Allegheny and State of Pennsylvania, citizens of the United States, have invented new and useful Improvements in Protectors for Igniting Material in Signal-Torches, of which the following is a specification.

Our invention relates to improvements in protectors for igniting material in signal-torches.

The object of our invention is to provide a protector for the complementary material carried by the end of the torch-covering to prevent the same from wearing off and also from becoming damp and destroying the properties of said material.

Our invention consists in a torch of any description which carries igniting material on its outer end for the purpose of lighting the torch and having a protector thereon for the purpose of protecting the said igniting material from moisture. In devices of this character the end of the covering carries a complementary material adapted to ignite the material carried by the torch, and in order to protect said material carried by the cap we provide a cover for said material which is readily applied and which is simple, cheap, and more effective than those heretofore made and one in which said protector is readily removed without injuring the complementary material.

In the accompanying drawings, Figure 1 is a perspective view looking down upon the end of the cap-protector. Fig. 2 is a vertical longitudinal sectional view. Fig. 3 is an enlarged detached view of the detaching member.

Referring now to the drawings, A represents a torch, which may be of any desired structure, but preferably cylindrical, as shown in the drawings.

B is a cover which is adapted to pass over the end a of the torch which carries the igniting material a', preferably like that used on ordinary safety-matches or similar material. The outer end b of the cap B is provided with a complementary material b', adapted to ignite the material carried by the end of the torch, and when it is desired to ignite the torch the cover is removed and the

end carrying the complementary material is rubbed across the igniting material. In order to protect the complementary material from exposure to moisture, and thus destroying the properties of said complementary material, we provide a rounded member C, which is just the size of the end of the cap and rests loosely thereon, and said member is provided with an elongated downwardly-extending member c, which is bent down along the side of the cap B in a manner clearly shown in Fig. 1. In order to firmly hold the said member C on the end of the cover, and thus perfectly seal the end of the cover, we provide a wrapper or protector D, which is preferably oblong in shape and which is wrapped around the side of the cover and the downwardly-extending tongue and cemented, and thus holds the tongue c in its downward position, the said tongue being of a length to extend considerably below the wrapper or protector D, thus leaving a portion c for grasping the same, the purpose of which will be more fully hereinafter described. The upper end d of said wrapper or protector extends considerably above the upper end of the cover and is folded down upon the disk-shaped member C and cemented thereto at d', thus completely closing the end of the cover and making a more perfect protector for the complementary material.

When it is desired to use the torch, the cap B is removed therefrom, and by taking hold of the lower end c' of the downwardly-extending tongue C and pulling it, it will be seen that the wrapper or protector is torn on the sides, and as the tongue is continued to be pulled the disk C, carried by the tongue, is torn away, carrying with it the upper end d of the wrapper or protector which is cemented thereto, thus leaving the whole upper end carrying the complementary material exposed, so that it may be used to ignite the igniting material carried by the torch. The complementary material b' practically covers the outer end of the cap, and in order to insure of the removal of all of the wrapper above the material we make the tape of a width practically covering the complementary material. The wrapper being of paper and cemented to both the cap and the tape, it will be seen that by pulling the tape it positively removes all of the wrapper above the complementary material, so that it can be readily brought in contact with the igniting

material of the torch. The wrapper is of an oblong sheet of paper and is wrapped and folded around the cap and cemented to both the cap and the tape.

5 It will be observed from Fig. 2 of the drawings that the igniting material is applied to a plug which is in the outer end of the tube, and the wrapper passes over the end of said plug and is secured to the side of the tube and 10 serves to hold the plug within the end of the tube.

Having thus described our invention, what we claim, and desire to secure by Letters Patent, is—

15 A fusee, comprising a body portion, a cap carried thereby and having a complementary material carried by its outer end and substantially covering the same, a tape extending across and practically coextensive with 20 and covering said complementary material,

and a wrapper formed of a sheet of paper and wrapped and folded around the cap and cemented thereto and to the tape, whereby the entire wrapper above the complementary material is removed with the tape, so that 25 the complementary material may be brought into engagement with the igniting material of the fusee.

In testimony whereof we have hereunto set our hands in the presence of the subscr- 30 ing witnesses.

ROBERT M. CLARK.
JOHN G. BENNETT.
